[57] CLAIM

The ornamental design for a fluorescent lamp, as shown and described.

DESCRIPTION

FIG. 1 is a perspective view of the top, front and left side of a fluorescent lamp showing our new design;

FIG. 2 is a front elevational view thereof;

FIG. 3 is a top plan view thereof;

FIG. 4 is a bottom plan view thereof;

FIG. 5 is a right side elevational view thereof;

FIG. 6 is a rear elevational view thereof;

FIG. 7 is a perspective view of the top, front and left side of a modified fluorescent lamp showing our new design, the right side view being a mirror image of the left side view thereof;

FIG. 8 is a front elevational view thereof, the rear elevational view being a mirror image thereof; and,

FIG. 9 is a top plan view thereof, the bottom plan view being similar to the bottom plan view of FIG. 4, but with the outer periphery having a configuration the same as the outer periphery in FIG. 9.
